JOHN L. MCKINDLEY AND SAMUEL B. KINDY, OF TORONTO, CANADA.

AUTOMATIC PRESS-TRIP.

1,217,971.

Specification of Letters Patent.

Patented Mar. 6, 1917.

Application filed January 21, 1915. Serial No. 3,603.

To all whom it may concern:

Be it known that we, JOHN L. MCKINDLEY and SAMUEL B. KINDY, subjects of the King of Great Britain, residing at Toronto, 5 Canada, have invented certain new and useful Improvements in Automatic Press-Trips, of which the following is a specification.

This invention relates to improvements in 10 automatic printing press trips and has to do more particularly with an improved attachment consisting of an actuating means for operating press trip mechanism which is initially installed with the press.

15 It is one of the objects of this invention to provide an electrically operated actuating means for the trip mechanism, and there is involved in this improvement a novel sheet controlled means, which constitutes, in practice, a make and break device for opening and closing circuit, such make and break device being controlled by the said sheet.

A further object of the invention is to incorporate in the circuit of the actuating 25 means a timer make and break device which will serve to close circuit and render the sheet controlled make and break operative, only during sheet feeding periods, so as thereby to greatly economize the batteries 30 or like source of current.

The invention also involves the novel feature of providing a sheet controlled make and break device, certain members of which are in the form of feelers, which are arranged to coact with the feed board tongues 35 in such a manner as to dispense with the necessity of employing drop guides.

A still further object of the invention is to provide feelers which are independently 40 movable toward and away from the feed board tongues, thereby rendering the feelers self adjustable as regards different thicknesses of paper and always insuring contact of the feelers with the feed board tongue so 45 as to complete circuit, when such parts are in the form of circuit terminals, to energize and actuate the press trip mechanism.

In accordance with the device of our invention, the usual foot trip mechanism may 50 be used without regard as to whether or not our invention is applied to the press, as

either can operate to actuate the trip mechanism without interference from the other.

Numerous other objects and features of the invention will be more fully described 55 in connection with the accompanying drawings and will be more particularly pointed out in and by the appended claims.

In the drawings:—

Figure 1 is a perspective view of portions 60 of a press which is shown equipped with a trip mechanism and also with the device of our device for actuating, or in other words, permitting operation of the trip mechanism.

Fig. 2 is a perspective of one of the circuit 65 terminals or feelers in circuit closing relation with one of the feed board tongues, adjacent mechanism being also shown.

Fig. 3 is a perspective view of a driving and operating cam and also of an improved 70 timer make and break device.

Fig. 4 is a sectional view of the shaft shown in Fig. 3 illustrating a ratchet thereon in elevation.

Fig. 5 is a similar view illustrating the 75 cam in elevation.

Fig. 6 is a side elevation of one of the drop blocks as shown in Fig. 2.

Like characters of reference designate similar parts throughout the different figures of the drawings.

As illustrated, 1 designates the frame of the press, as a whole, and 2 designates the cam shaft with which the press is initially provided. A controlling cam 3, which may 85 preferably be split to facilitate ready attachment when the invention is in the form of an attachment, the cam 3 being loosely mounted upon cam shaft 2. A split ratchet 4, having a hub 5, is keyed or otherwise fixed 90 to cam shaft 2 and is provided with one ratchet tooth, as indicated at 6. The cam 3 is provided with a ratchet pawl 7, mounted on the cam at 8, and which may either be initially resilient or spring-controlled so as 95 to always engage the periphery of ratchet 4 and seek a driving position in the recess or tooth 6, when such parts are in registry. The direction of rotation of the cam shaft 2, is contra-clockwise, viewed from Fig. 1, and 100 therefore it will be seen that as the ratchet 4 rotates, the tooth will engage pawl 7 and

advance or drive the cam 3 in prescribed relation with ratchet 4. Furthermore, the pawl and ratchet device permits of backing up the press, for any of the usual purposes, 5 and insures connection of the cam with the cam shaft in proper timed relation by reason of the fact that there is only one tooth for engagement with the pawl, when the shaft 2, is driven in its normal direction of rotation.

That portion of the press trip mechanism which it is pertinent to describe to illustrate the application of the device of our invention thereto, includes a spring actuated member or arm 9, mounted on shaft 10, and having a roller 11 for engagement with the periphery of cam 3. At the upper end of arm 9 is pivoted at 12, one end of a spring reciprocated bar 13 to which a spring 14 is applied in such a manner as to normally urge bar 13 and arm 9 to the right of Fig. 1. The periphery of cam 3, from point α to α , serves to prevent actuation of arm 9 under spring 14 while the roller 11 is in engagement with this retaining peripheral portion from α to α , which I will designate as 15. The cam 3 has a releasing portion 16, which is cut away and is of shorter radii than the retaining portion 15, and which 30 permits of actuation of the press trip by the spring 14 on a mis-feed or for other conditions which may be imposed. To arm 9, at 17, is pivoted one end of feed detent link 18, the remaining end of which is pivoted at 19, to one arm of a bell crank lever 20. The remaining arm 21, of said bell crank lever, is pivoted at 22, to a raising link 23. Raising link 23 is connected to mechanism which will be designated as a whole at 24, 40 and the operation of which serves to trip the press. A foot trip, designated as a whole at 25, also operates in connection with the mechanism 24 to trip the press when the operator desires to perform this operation 45 independently of the device of our invention.

The feed board is indicated as a whole at 26, and tongues 27 project therefrom and in the present invention, perform the function 50 of circuit terminals. Feelers 28, having hook-shaped ends 29 and balled terminals, function as circuit terminals for coaction with the tongue terminals 27, to close circuit through apparatus which will presently be 55 described. The feelers 28, also function in the place of and in substitution of the usual drop guides and act to steady the sheet before guides 31 raise, and until the sheet is engaged by the grippers of the cylinder. A 60 novel form of mounting is provided for the feelers 28, the shanks thereof being pivoted to feeler blocks 32, at 33, for independent movement of the feelers with respect to each other irrespective of the thickness of the

paper being fed. Upon downward movement of the feelers 28, the interposed sheet of paper will prevent contact between the feeler terminals 28 and the tongue terminals 27, thereby holding the circuit open and preventing electrical energization of the actuating mechanism. If for any reason whatsoever, such as out of time feeding, the paper was not interposed between the feelers 28 and the tongues 27, then circuit will be closed and the device of our invention would 75 be energized to trip the press.

Now referring more particularly to the mounting of the feelers 28, the blocks 32 are shown formed in two parts, more particularly in Fig. 6, indicated at 32 and 34. A 80 block of insulation 35 is interposed between the block sections 32 and 34 and the parts are secured together by means such as rivets 36, which pass through extensions 37 with which the insulating block 35 is formed. Now the feeler blocks 32 are mounted upon a drop guide shaft 38, suitably journaled in the frame of the press, as indicated at 39. Actuating means for the shaft 38 is not 85 shown as it may be of the usual type. Drop 90 blocks, at the ends of the shaft 38, one only being shown, is indicated at 40, the portion 40 being insulated from the shaft portion 41 by an insulating block 42, in a manner similar to the feeler blocks 32. A conducting or 95 live shaft or rod 43 is mounted in the drop and feeler blocks in such a manner as to lie at one side of the points of pivotal mounting 33 of the feeler blocks 32, and to also 100 cross the feelers, preferably underneath the same, as indicated at 44, so as to permit free upward movement of the feelers independently of each other and of the rod 43, but to prevent downward movement of the 105 feelers 28 in case the mounting therefor, through actuation of shaft 38, is elevated. A rest 45, is mounted on each end of the frame 1, only one being shown, so that the feelers and their mounting can be swung 110 back into an inoperative position with the ends of the rod 43 seating in the rest 45.

The circuit, and the parts interposed therein for operation of the device of our invention, will next be described in detail.

The source of current is indicated at 46, 115 in the form of batteries, which are electrically connected with each other by conductors 47, 48 and 49. One limb of the circuit designated at 50, leads from one pole of the source of current to a magnet 51. From magnet 51, a conductor of the circuit designated at 52, is connected with the conducting or live rod 43. From said rod 43, current is conveyed to the blocks 32 to 120 feelers 28, and if the latter are in contact with tongue terminals 27, through the press frame to one member 53 of a timer make and break device. The member 53 of said 125

timer make and break device is mounted upon cam 3, as will be more clearly seen by reference to Fig. 3, and a spring or like wiper 54 coacts with the timer contact 53 to close the circuit during feeding periods to maintain the circuit open at other times so as to effect the greatest battery economy. Wiper 54 is mounted upon a stub shaft 55, suitably insulated from the frame 1 of the press, and a conductor 56 connects wiper 54 with the remaining pole of the source of current. It will now be seen that the insulating blocks 35 and 42 prevent current from short circuiting through the press without taking its course through the feelers and feed board tongues, the latter constituting circuit terminals.

A detent device is provided for holding the trip mechanism against operation even when the roller 11 is released for operation by the releasing portion 16 of the cam 3.

As illustrated, the detent link 18 is provided with a detent notch for engagement by the pawl end 57 of a detent which is pivoted to the press frame 1 at 58. The detent is in the form of a bell crank lever having a magnet arm 59 which is within the field of the magnet 51 so as to be attracted thereby to release the trip mechanism for actuation under the action of spring 14 when the circuit has been closed. The pawl end 57 is somewhat wider than the detent link 18 so as to slightly overlap the periphery of cam 3. Cam 3 has two actuating or raised portions 60 and 61 which serve to elevate the detent as the cam rotates, twice in each revolution of the latter, so as to reduce wear of the working parts.

It will now be clear, that if the feelers 28 descend upon a sheet of paper which has been fed in timely manner, the paper will insulate feeler terminals from the tongue terminals and hold the circuit open. If however a sheet has not been fed in timely manner, then the feelers 28 will descend upon the tongues 27, and in direct contact therewith, so as to close circuit and effect operation of the press trip mechanism. It will also be noted that it is not necessary for both of the feelers to contact with the tongues, as any imperfect or untimely feeding of the sheet for making either feelers to contact with its respective tongue, will close circuit and effect trip operation.

It will also be seen that when the feelers have been thrown into neutral position, or an inoperative position, with the rod 43 seated on the rest 45, it will be possible to run the press tripped when the feed board 60 is raised, it being not necessary to lower the feed board to draw an impression because of the fact the feelers can be thrown to a back limit out of contact position.

The use of our invention will insure more

perfect register, since it will allow the feeders to devote all of their time to feeding sheets thus preventing mis-tripping and avoiding wash-ups on the cylinder.

By means of the pawl 7 and the one-tooth ratchet, the press may be backed without injury to the machine, and when driven in a feeding direction, the parts will always be in timed relation.

It will also be noted that the feelers 28 serve to lock out a sheet which has been fed too late, the sheet being left on the feed board until the guides drop so that it may be properly placed to the guides.

While we have herein shown one specific form of our invention, we do not wish to be limited thereto except for such limitations as the claims may import.

We claim:

1. In a printing press, a trip mechanism, electrical means for actuating said mechanism including tongue and feeler terminals for closing said circuit when in engagement and opening said circuit when a sheet is fed therebetween, said feelers being independently movable with respect to each other toward and away from said tongues, substantially as described.

2. In a printing press, trip mechanism actuating means including a live rod movable toward and from feed positions, and feelers mounted for independent movement with respect to each other and with respect to said rod and extending across the latter to be shifted thereby, substantially as described.

3. In a printing press, trip mechanism actuating means including a circuit having tongue and feeler terminals for controlling said circuit by a fed sheet, and mounting means for said feelers comprising a drop shaft, drop and feeler blocks on said shaft, said feelers being pivotally mounted in said feeler blocks, and a live rod journaled in said blocks and disposed across said feelers and at one side of the points of pivotal mounting of the latter, substantially as described.

4. In a printing press, trip mechanism actuating means including a circuit having tongue and feeler terminals for controlling said circuit by a fed sheet, and mounting means for said feelers comprising pivotally mounted blocks pivotally connected with said feelers, and a live rod mounted in said blocks and disposed across said feelers and at one side of the points of pivotal connection of the latter with said blocks, substantially as described.

5. In a printing press, trip mechanism including a spring actuated member, a cam shaft, a cam loose on said shaft for controlling said member, a detent normally holding said trip mechanism against operation,

21
a ratchet fixed on said shaft, a ratchet pawl
on said cam for engagement with said
ratchet to drive said cam, a timer contact
on said cam, a circuit grounded through the
5 press and including sheet actuated terminals
for opening and closing said circuit,
a magnet in said circuit for operating said
detent to release said mechanism, and a fixed
timer contact in said circuit and insulated
10 from the press for engagement with said

cam contact to close said circuit and render
said sheet controlled terminals operative at
feeding periods, substantially as described.

In testimony whereof we affix our signatures
in presence of two witnesses.

JOHN L. McKINDLEY.
SAMUEL B. KINDY.
